C. D. BATES.
INCANDESCENT LAMP GLOBE CHANGER.
APPLICATION FILED AUG. 12, 1909.

1,056,084.

Patented Mar. 18, 1913.

UNITED STATES PATENT OFFICE.

CARL D. BATES, OF CHICAGO, ILLINOIS.

INCANDESCENT-LAMP-GLOBE CHANGER.

1,056,084.

Specification of Letters Patent. Patented Mar. 18, 1913.

Application filed August 12, 1909. Serial No. 512,608.

To all whom it may concern:

Be it known that I, CARL D. BATES, a citizen of the United States, residing at Chicago, in the county of Cook and State of Illinois, have invented a new and useful Incandescent-Lamp-Globe Changer, of which the following is a specification.

My invention relates to devices used to attach and detach electric light bulbs located at a considerable distance above the floor and without the use of a ladder.

The objects of my improvements are first, to make a device which is adjustable to any size bulb; second, to provide a novel arrangement of coupling the sections of the pole; third, to arrange the device so that it can be used as either a stiff pole or rod or a pole with a flexible joint; fourth, to make the bulb gripping fingers of an improved construction; fifth, to make a cheap, simple and durable device and other features to become apparent from the description to follow.

My invention comprises a plurality of flat metal spring fingers slightly curved secured in the end of a pole or rod so arranged as to normally spring apart far enough to fit over the largest size electric bulb. A ring is slipped up around the shanks of the spring fingers more or less to reduce the proximity of the extremities of the spring fingers so as to have them fit snugly over any desired sized bulb. The globe gripping end of the pole is flexibly connected to the main pole preferably by a coiled spring, the coils of which are so flattened as to make the spring very flexible as to its bending capacity but very stiff as to its twisting capacity. The several sections of the pole are detachably secured together by means of angular off-sets on the abutting ends of the pole.

To describe my invention so that others versed in the art to which it pertains may make and use same, I have illustrated it on the accompanying sheet of drawing forming a part of this specification, in which:

Figure 1 is a side elevation partly in section of a device embodying my invention; Fig. 2, is a similar view showing the device adjusted to a different position; Fig. 3, is a section on line 3—3 of Fig. 1, and Fig. 4, is a section on line 4—4 of Fig. 1. Fig. 5, is a sectional view in elevation of an elevated joint connection.

Similar reference characters refer to similar parts throughout the several views.

The pole 5 is made up of several detachable sections as 5^a, 5^b, 5^c and 5^d, the abutting ends of which are provided with stepped off-sets or shoulders which in turn are surrounded by snugly fitting collars or sleeves 6^a, 6^b and 6^c. To secure the collars 6^a, 6^b and 6^c in proper position they are secured to one of the adjacent ends of the pole sections in any desired manner as by rivets. 60 The purpose of the shouldered abutting ends of the pole sections is to lock them rigidly together in respect to a twisting or turning action but have them free to separate by a longitudinal pull.

70 The pole 5 has secured to its upper end one end of a coiled spring 8, the other end of which is secured to the tip 9, thus flexibly connecting pole 5 to tip 9 and at the same time substantially rigidly connecting them in respect to a twisting or turning motion. The tip 9 comprises a wood block 10 which is driven into a sleeve or tubing 11. For some purposes it is desirable to lock the tip 9 rigidly to pole 5 and for this 80 purpose I provide a split sleeve 12 which is somewhat longer than the spring 8, to fit snugly over the exterior of tubing 11 and upper end of pole 5. The sleeve 12 is split on a spiral line to effect a better grip on 85 the co-operating parts.

The tubing 11 is provided with an annular bead 13 which serves as a bearing for the ring or collar 14 which fits loosely about the tubing 11 and is provided with an ear 90 14' to which is secured one end of a cord 15. The cord 15 hangs down to within reach of the operator who pulls down on same when it is desired to flex the tip 9 as seen in Fig. 2.

95 By this construction the operator can flex the tip 9 so it will extend at a right angle to the pole 5 or even at an acute angle if found necessary.

The lamp gripping device 16 comprises 100 the flat spring members 17 which are rigidly secured in tip 9 between the tubing 11 and wood block 10 as seen in Figs. 1 and 3. Extending up from the tip 9 the spring members 17 are straight for some distance as 105 seen at 18 say for about one-half their length, the balance of their length they are bowed outwardly to somewhat conform to the shape of a lamp bulb. The bowed portion of the members 17 are 110 covered with rubber tubing 20 or other suitable substance, but the extreme ends 19 of

the members 17 are left bare so that when brought into contact with the glass bulb they will easily slide over the surface and spread to grip about the bulb with the rubber covered portions.

5 The members 17 are so attached to the tip 9 as to have their extremities normally spread apart to fit over the largest sized bulb and when it is desired to grip a smaller 10 bulb the ring 21 is moved upward on the part 18 of members 17 a sufficient distance to reduce the gripping portion to the required size. To retain the ring 21 at any 15 desired position the coöperating surfaces of the members 17 may be provided with indentations 22.

Having thus fully described my invention what I claim as new and desire to secure 20 by Letters Patent of the United States is:—

20 In a device of the character described, a pole comprising detachable sections, the abutting ends of which are provided with approximately step-shaped shoulders interlocking said sections, a spiral spring secured 25 at one end of one of said detachable pole sections, a tip comprising a tube having a

wooden block inserted therein, a plurality of flat spring members rigidly secured on said tip between the tube and wooden block, said members being provided with a straight 30 portion adjacent the tip, each member provided with an indentation alining with the indentation on the adjacent members, said spring members being curved at their outer ends, said curved portion being provided 35 with a covering, a ring adapted to slide over the straight portion of said spring members, and seat in the indentations formed thereon for holding the curved ends in closer relation, a spirally split sleeve 40 adapted to slide over the spiral spring and of sufficient length to rigidly connect the end of the section and tip, as and for the purpose set forth.

In testimony whereof I have signed my 45 name to this specification in presence of two subscribing witnesses this 2nd day of July 1909, at Chicago, Illinois.

CARL D. BATES.
